M. STARMER

BELT

Filed Oct. 18, 1921.

Inventor:

Mary Starmer
Cecilie B. Brock
Atty.

UNITED STATES PATENT OFFICE.

MARY STARMER, OF NEWPORT NEWS, VIRGINIA.

BELT.

Application filed October 18, 1921. Serial No. 508,584.

To all whom it may concern:

Be it known that I, MARY STARMER, a citizen of the United States, residing at Newport News, in the county of Warwick and State of Virginia, have invented certain new and useful Improvements in Belts, of which the following is a specification.

My present invention relates to improvements in garment supporters of the waist-line or belt type adapted for use by men and women, and especially adapted for adjustment to the body of the wearer, as a supporter for garments, with varying degrees of tightness to insure the desired comfort and convenience of the wearer.

The primary object of the invention is the provision of a device of this character which may readily be adjusted to different sizes of waistlines, and in addition may with convenience and dispatch be buckled for wear, or released from the wearer, as desired. And while I have illustrated, and shall hereinafter describe the invention as embodied in a waist line belt, it will be obvious that the device is applicable for use in securing together the ends of straps or webbing, as in suspenders, or for straps on trousers, vests, and similar garments.

In the accompanying drawings I have illustrated one complete example of the physical embodiment of my invention wherein the parts are combined and arranged in a waist line belt, according to the best mode I have thus far devised for the practical application of the principles of my invention, and wherein the novel features of the invention are set forth in the belt buckle and the adjusting buckle which cooperates therewith.

Figure 1 is a front view of the front portion of a waist line belt, as it appears in use, showing my invention, parts being indicated in dotted lines.

Figure 2 is a rear or inner side view of the belt as seen in Fig. 1.

Figure 3 is an inner face view of the belt buckle plate attached at one end of the belt.

Figure 4 is an inner view of the belt buckle keeper which is attached at the opposite end of the belt and co-acts with the buckle plate for securing the ends together.

Figure 5 is a transverse, vertical sectional view at line 5—5 of Fig. 1.

Figure 6 is a top edge view of the belt of Figure 1.

Figure 7 is a horizontal sectional view at line 7—7 of Fig. 1.

In the preferred form of the invention as shown in the drawings, the belt may be of webbing, fabric, or other suitable material of proper dimensions and shape, of which the two ends 1 and 2 are to be connected together.

In the utilization of the invention as a belt for waistline wear, the end 2 of the belt carries the buckle plate 3, which may be of silver, or other suitable metal or material, and ornamented on its front face as desired. As shown this plate, which is rectangular in form, is provided at one end with a vertical bar 4, and end slot 5 through which the end 2 of the belt is passed and turned back under the bar 6 to form a loop 7. The bar 6, as best seen in Fig. 3, is the end of a back plate 8, turned back from the front end of the buckle plate, and the back plate lies parallel with the front or buckle plate and provides a space for the loop end 7 of the belt end 2. Bar 6 is fashioned by stamping or cutting a zig-zag or toothed slot 9 in the back plate which extends from near the top to near the bottom of the back plate, and it will readily be seen that when the end 2 of the belt is passed through slot 5, then passed through the toothed slot 9 from the back of the back plate and located in the space between the web end and the back plate, the loop thus formed is firmly gripped by the toothed slot 9 and the belt buckle plate is retained on the end of the belt.

Along the top edge of the buckle-plate an ornamental flange 10 is provided, a notch 11 being provided at the front end of the plate, by terminating this flange a short distance from the bend between the front plate and the back plate, for a purpose to be described.

The back plate 8 is also fashioned with a horizontally extending, centrally located, short bar 12, offset from the plane of the back plate, and the back plate is cut out or slotted at 13 14 respectively above and be-

low the cross bar in order that the bar and the metal thereabout may be frictionally engaged by and retain in position, a tongue 15 on the keeper 16 complementary to the 5 buckle plate.

The keeper 16 is a flat, rectangular, vertically disposed metal plate, slotted at 17 and slotted at 18, to form the downwardly projecting tongue 15, and the tongue is of sufficient length to permit its free end to be slightly pushed outwardly or away from the body of the wearer, in order that the end of the tongue may be entered behind the cross bar 12, and then said tongue slipped or

shoved downwardly along the outer face of the back plate to lock the keeper to the buckle plate. The resiliency of the metal in the back plate and the keeper plate permits this movement, and when the keeper is pressed home, the parts are frictionally held. At the upper end the keeper-plate is fashioned with a flange 19 which fits into and occupies the notch 11 formed in the corner of the buckle plate.

25 The keeper plate is attached to the end 1 of the belt, by the formation of a loop 20, passed around a tubular friction bar 21 which latter is supported on the keeper bar 22. The integral bar 22 which is provided 30 at the front end of the keeper plate is stamped therefrom and forms one wall of the slot 17.

The size of the loop 20 may be varied to take up slack in the belt or to lengthen 35 the belt, and for this purpose I utilize an adjusting buckle, preferably made up of a single piece of stiff wire and bent to shape as shown. The adjustable buckle comprises a stiff, vertical bar 23 around which the bent 40 end of the loop passes, and near the top and bottom of this bar the wire is bent outwardly, or away from the body of the wearer, and formed with a pair of heads 24, 25 which lie in a vertical plane, parallel with the belt and extending toward the buckle plate. Returning from these two 45 heads, in each case, a strand of wire is passed through a hole in the loop end, and the wire is then bent as at 26, 27 over the top edge and under the bottom edge of the 50 end 1, the single strand being brought out in front of the end piece 1. A pair of curved portions 28, 29 are formed as shown in front of the web end 1 and these portions are crossed and terminate in smaller loops 30, 31. These smaller loops each terminates in a return bend or hook 32, 33 and the hooks are fashioned with sharpened prongs 34 that enter the webbing from the outside of 55 the belt, as shown.

The smaller loops 30—31 form a thumb piece beneath which the thumb may be slipped, and by forcing outwardly these loops, the prongs 34 may be released from the 60 webbing of the belt. When the prongs are

released the end 1 of the belt may be pulled or shoved between the curved guide portions 28—29 and the heads 24—25. Pulling the web through this space will shorten the loop 20 and lengthen the belt, while pushing the 70 web through the space will lengthen the loop 20 and shorten the belt. By this means the length of the belt may be adjusted as desired, and when the thumb is withdrawn, the resiliency of the metal wire of the adjusting buckle will restore the prongs 34 to position in order that they may enter the front face of the web end 1.

From the above description taken in connection with my drawings it is evident that 80 the length of the belt may with facility be adjusted, and that the belt may be buckled or unbuckled with convenience. Also that when once adjusted and buckled, the belt will remain in proper position, supporting the garments in a comfortable manner, and presenting a neat and finished appearance.

Having thus fully described my invention, what I claim as new and desire to secure by 90 Letters Patent is:—

1. The combination in a device as described with belt ends, of a buckle plate having a back plate and an offset cross bar thereon, and a keeper plate having a vertically disposed tongue thereon to engage said cross bar.

2. The combination with a belt end, of a buckle plate formed with a slotted back plate for attachment of said end, a keeper plate on the other belt end and said end formed with a loop for attachment to said plate, a locking member on the keeper plate for co-action with said back plate, and a slack adjusting buckle connected with said 105 loop.

3. The combination with a belt end, of a buckle plate having a back plate and said back plate fashioned with a slot having zig-zig walls to retain said belt end, a cross bar on said back plate, a keeper plate connected with a loop on the other belt end, a friction tongue on said keeper plate for co-action with said bar, and a slack adjusting buckle connected with said loop.

4. The combination with a buckle-plate having a back plate and a cross bar on said back plate, of a keeper plate having a locking tongue adapted to co-act with said cross bar.

5. The combination with a buckle plate having a back plate and a flange terminating adjacent to said back plate, of a keeper plate having a flange complementary to the flange of the buckle plate, a cross bar on said back plate, and a locking tongue on said keeper plate for co-action with said cross bar.

6. The combination in a belt with its connecting buckle, and web ends, of an ad-
